DESIGN FOR A SUPPORT FOR A FRENCH- TYPE TELEPHONE

Michael J. Conlon, Jr., New York, N. Y.

Application February 9, 1939, Serial No. 82,897

Term of patent 3½ years

To all whom it may concern:

Be it known that I, Michael J. Conlon, Jr., a citizen of the United States of America, residing in the city, county, and State of New York, have invented a new, original, and ornamental Design for a Support for a French-Type Telephone, of which the following is a specification, reference being had to the accompanying drawing, forming part thereof.

In the accompanying drawing:

Fig. 1 is a perspective view of a support for a French-type telephone, embodying my design;

Fig. 2 is an enlarged fragmentary side elevational view of the same; and

Fig. 3 is an enlarged fragmentary front elevational view of the same.

The characteristic features of my design are shown in the solid lines in the drawing.

I claim:

The ornamental design for a support for a French-type telephone, substantially as shown and described.

MICHAEL J. CONLON, JR.
